UNITED STATES PATENT OFFICE

2,172,039

ROTARY INTERNAL COMBUSTION ENGINE

Benjamin Shore, New Malden, England

Application January 22, 1936, Serial No. 60,308
In Great Britain January 23, 1935

4 Claims. (Cl. 123—14)

This invention relates to rotary internal combustion engines comprising a rotor revolving within a cylindrical bore casing with the annular space between the rotor and bore divided by equally spaced abutments into a number of compartments.

The primary object of said invention is to provide a rotary internal combustion engine of simplified construction and of great efficiency. A further object is to provide an engine in which a substantially uniform torque is provided resulting in smoothness of running. Another object of the said invention is to produce an internal combustion engine in which the power developed is large compared with its weight thus rendering it particularly suited for use in aircraft.

These and other objects of my invention will be apparent from the appended description having reference to the accompanying drawings which illustrate various examples and modifications of rotary engines constructed in accordance with my invention.

It will be understood that various constructional details obviously necessary and apparent to those skilled in the art have been omitted and in the drawings:

Fig. 1 is an elevation, partly in section, of a rotary internal combustion engine constructed in accordance with my invention.

Fig. 2 is a sectional side view, on the line 2—2 of Fig. 1.

Fig. 3 is a fragmentary sectional view on an enlarged scale through the rotor and stator showing one series of abutments.

Fig. 4 is a view similar to Fig. 3 showing the rotor in a different position.

Fig. 5 is a fragmentary view of a modification.

Like reference numerals indicate like parts in the drawings.

Referring first to Figs. 1 and 2 the rotor R is mounted by key 1a or other suitable means on a shaft 1, said rotor comprising a bush 2 and radial arms 3 supporting a drum like member 4 the circumferential surface of which carries transverse equally spaced apart vanes 5.

The stator drum consists of an enclosing casing comprising a main member or annulus 6, with suitable side plates 7, said main member being formed with channels or spaces, as later described for the transfer of gases and to house the various valves, abutments and the like, and the side plates are formed with spaces for the passage therethrough of operating rods for the abutments and valves. The drum like member 4 is provided at each side with an annular groove 8 and the side

plates 7 of the casing are housed in said grooves (with suitable sealing means not shown) to allow for rotation of the rotor and for equal sized compartments 9 between the rotor and bore of the casing, the size of which is determined by the relative diameter of the rotor and bore, and the number of compartments. A number or series of abutments half as many as the number of compartments and also serving as valves are provided, and each series comprise three, the said abutments being gas tight within suitable channels 17—18 in the casing. These abutments which extend completely across the compartments comprise induction abutments 10 in channels 17, transfer or second abutments 11 and compression-charge-carrying, or firing, abutments 12 in channels 18. Said abutments are urged by means of compression springs 13, on to the rotor surface, so as to form a partition when allowed to drop. Any suitable means may be provided, however, for urging the abutments on to the rotor surface.

The inlet from the carburettor or like supply is taken through a duct 14 which is integral with a bearing of the shaft 1 and is carried to the inlet abutments by arms 15 which communicate with passage ways 16 in the casing 6. Said passage ways communicate with the channels 17, and with portways 19 in the induction abutments 10 when same form partitions. In back (with respect to the clockwise direction of rotation of the rotor and cycle of operations) of the induction abutments, exhaust ports or passages 20 are provided, leading to a suitable manifold (not shown).

In order to allow for the insertion and removal of the compression springs 13, tapped holes 21a are provided in the cover through which the springs may be inserted, suitable screw in closures 21 (Fig. 2) being provided.

The abutments are lifted against, or allowed to drop under the influence of the springs 13 by means of cam-tracks 22, 23 at each side and co-operating means 25, 27 on the abutments. Two cam-tracks 22, 23 integral with the rotor R at each side thereof, are provided the first 22 to actuate both the induction and transfer abutments, the second 23, to actuate the firing abutments 12. The transfer abutments 11 carry lateral arms 24, having rollers 25 which engage the cam-tracks 22. A similar arrangement actuates the inlet abutments whilst lateral arms 26 having rollers 27 which engage the cam-track 23, actuate the firing abutment. The cam-track 22 is similar in contour to the rotor surface so that both induction and transfer abutments follow

the contour of the rotor but the cam-track 23 is contoured to ensure that the third abutments are held clear of the rotor surface except when firing occurs as later described, and for a suitable period thereafter. All the lateral arms 24, 26 pass through suitable slots in the side plates 7, the slots for a firing abutment 12 being designated by the numeral 28 in Fig. 2.

A valve mechanism is provided for ensuring cut off between low and high pressure sides in a compartment when a vane 5 is passing the pair of abutments until after return to normal position of the said pair of pressure and firing abutments. A portway 29 in the annular member 6, communicates with a fluid space 30, said space or chamber being formed with a seat 31 and communicating with another portway 32 in the member 6. These two portways 29, 32 are in communication or cut off, depending upon the position of the valve head 33. The head is carried on a stem 34 which projects through a side plate 7 and carries a roller 35, engaging with a cam track 36, which raises the head 33, or enables same to be closed by the compression spring 37. It will of course be understood from the drawings that one mechanism above described is provided for each series of abutments.

The transfer abutment 11 of each series has therein a passage way 38, whilst the firing abutment 12 has a cooperating passage way 39 which is in communication with a compression space or pocket 40 in the said abutment. This space 40 communicates with a part of a compartment towards the rear edge of a vane when the abutment 12 is dropped.

It will be observed from the later description that the portways 29, fluid space 30, and portways 32 form the means for transferring the induced charge to the portways 38, 39 on the pair of abutments 11, 12.

Reference will now be made to Figs. 3 and 4, which show one complete series of abutments and valve, said figures illustrating the operation of the engine, it being understood that all series of abutments synchronise.

In Fig. 3 the abutment 10 is spring urged on to the rotor in the position shown, having just completed its rise and fall to follow the contour of the passing vane 5, and in this position, the portways 16, 19 are aligned. It will be understood therefore that movement of the rotor will cause the charge from the carburettor or like supply, to be drawn into the portion of the compartment 9¹ between the said abutment 10 and the rear edge of the passing vane 5, until said vane reaches the abutment 11, when both the abutments 10 and 11 commence to lift. The movement of the abutment 10 cuts off the fuel supply, whilst the movement of the abutment 11 cuts off the passage between the fluid space 30 and the pocket 40. When in such position the compartment 9 between the two said abutments is filled with the induced charge, and further movement will start compressing the charge via the port 29 into the fluid space 30. The pocket 40 contains the previously compressed charge, and when the rotor is in the position illustrated in Fig. 3, with all abutments in a series urged on to the rotor or whilst the abutment 12 is following the contour of the rear edge of a vane this previously compressed charge is fired by suitable spark plugs P in the confined space between the pocket 40 and the rear edge of the vane just passed. In order that this charge in the pocket 40 shall not leak back into the low pressure fluid space 30 at the rear side

of the abutment 11, the valve 33 closes whilst the vane is passing the port 29, and whilst the abutments 11 and 12 are dropping. Reverting now to the induced charge above referred to, this is compressed into the fluid space 30 and portway 5 38 until the abutment 12 is lifted shortly after firing as will be seen from the shape of the cam 23, so that the passageways 38 and 39 align, the compressed charge passing into the pocket 40 until the following vane cuts off the portway 29 10 and the abutment 11 starts to lift. After a charge has been fired the explosive force against the rear edge of a vane just past impells the rotor and the abutment 12 is retracted into the casing, the compartment containing the exhausted gases will 15 pass round until the following vane after passing 11, 12, as before mentioned forces same through the exhaust passage 20 the forward inlet abutment 10 forming a partition. Thus it will be appreciated that the compartments are firing and 20 exhausting alternately and whilst the explosion occurs in the confined space of the compartment between the rear edge of a vane 5 and the front edge of the abutment 12, the other space between the front edge of a following vane and the abutment 11 is compressing a charge which after said 25 abutment 12 has lifted and is dropped again, passes into the pocket 40 of the firing abutment via the portways 32, 38 and 39.

In Fig. 4 the compartment 9¹ contains an induced charge, the pocket 40 a compressed charge, and both compartments 9¹E contain burnt gases, whilst in Fig. 3 the abutment 12 has dropped into firing position, transfer abutment 11 into sealing position, and abutments 10 to form an inlet for 35 the charge into the next compartment and also a partition for the diversion of exhaust gases.

In the example illustrated, five impulses are simultaneously produced, and as there are ten vanes or compartments fifty impulses will be 40 produced per revolution. In Figs. 3 and 4, sealing strips designated generally by the numeral 41, are provided on the vanes 5 and abutments 10, 11 and 12, said strips being urged by suitable springs within their slots. Also, to prevent 45 any undue percussion or pressure by the abutments, the chambers 17, 18 are both stepped at 42, and the abutments are correspondingly shaped. Thus the downward movement of the abutments is limited, sufficiently to prevent undue friction upon the rotor, whilst allowing adequate 50 sealing.

In the modification shown in Fig. 5 an arrangement is shown in which the size of the compartment as determined by the distance between 55 rotor surface and bore is such that the provision of vanes, the full distance between rotor and bore is impracticable. In order therefore to provide a seal a radially sliding blade 43 is housed in a slot in each vane 5', said blade being forced 60 outwardly by compression spring means 44 forming a partition across a compartment. The abutments 10', 11', 12' of each series are of a size 65 and have portways so disposed that they are not completely retracted into the compartments 17', 18' and the bore of the casing is curved both at 45 and 46, and the surface of the abutments shaped at 47, 48, and 49, that the cut off corner 50 of the blade 43 is guided thereby when passing the retracted abutments.

It will be understood that this construction enables compartments of greater volume to be provided compared with the embodiment previously described, for engines of similar overall size.

It will be understood that the casing is suitably 75

supported such as by means of a bed plate 58 (Fig. 1) and that the sparking plugs for firing will be suitably housed. In Fig. 2 a plug is shown fitted in the third abutment. However the plugs 5 P may be fitted in any suitable position so as to fire the charge, the position being determined by the details of design of the engine.

The firing of the charge will preferably take place an instant before the rotor is in the position shown in Fig. 1 so that the main impulsive effort is received when the vane is substantially 10 in the position shown.

I claim:

1. A rotary internal combustion engine comprising a rotor, a casing having a cylindrical bore and also provided with exhaust passages, means for mounting said rotor in said casing, the periphery of said rotor being spaced from said casing so that an annular space exists between the 20 rotor and the casing, a plurality of vanes on the rotor dividing said annular space into a plurality of compartments, means closing the sides of said compartments, a fuel supply member located adjacent and in front of each exhaust passage, said 25 fuel supply member mounted in the casing for movement between two positions in one of which it is effective to deliver fuel into said annular space and in the other of which it denies fuel delivery into said space, means tending constantly to move said member to its first mentioned 30 position, means whereby said member is movable to its second mentioned position simultaneously with movement of a vane across the same, a second member slidably mounted in the casing 35 in advance of said first mentioned member as regards the direction of rotation of the rotor, spring means constantly urging said second mentioned member inwardly against the periphery of the rotor, a chamber in communication with said 40 annular space between said first and second mentioned members, an abutment slidably mounted in the casing and having a compression pocket, spring means constantly urging said abutment against the periphery of the rotor, cam means 45 for outwardly moving said second mentioned member and said abutment, means for the supply of fuel from said chamber through said second mentioned member and said abutment into

the space between a vane and said abutment when a vane has passed by said abutment, and means for firing the fuel supplied to said space.

2. The combination as set forth in claim 1 in which the second mentioned member and the abutment are provided with cooperating ports disposed so that delivery of fuel from the chamber into the pocket of the abutment is denied except when said second mentioned member is projected across the said annular space and said abutment is retracted into the stator. 5

3. The combination as set forth in claim 1, wherein, the said chamber which communicates with the passage in the second mentioned member is provided with a cam and spring controlled 15 valve which closes while a vane is passing the port leading to the chamber and while the second mentioned member and abutment are dropping onto the rotor to prevent the compressed charge in the pocket from leaking back to the low pressure fluid space at the other side of the second mentioned member. 20

4. A rotary internal combustion engine comprising a rotor having vanes and a stator having a series of exhaust passages, said rotor and stator 25 having an annular space therebetween divided into a number of compartments by said vanes, pairs of contiguous and relatively sliding abutments each having fuel passages adapted to register during a portion of the relative movement between the abutments and one of said abutments having a pre-compressed charge-holding pocket, said abutments being spring urged toward the rotor and adapted to deliver said pre-compressed charge behind the vanes, mechanical means independent of the vanes for actuating the abutments of each pair to drop together onto the rotor behind each vane, means for supplying a pre-compressed charge to the abutments prior 30 to their dropping and means for causing the charge to be fired as both abutments of each pair drop, the number of pairs of abutments being half as many as the number of vanes forming compartments whereby the number of firing impulses per revolution of the rotor is equal to the 35 number of compartments times the number of pairs of abutments. 40
